RIM OR FLANGE PERFORATING DEVICE

Lawrence V. Whistler and Sanford A. Whistler,
Kenmore, N. Y.

Application October 27, 1941, Serial No. 416,690

7 Claims. (Cl. 164—94)

Our invention relates to a rim or flange perforating or punching machine or device adapted to be placed within a stamping or punching press or a die-set designed for use within a press, either of which has a ram and bed movable relatively and invariably in a vertical plane or at least in a plane trending toward the vertical.

One of the objects of our invention is to provide a simple, efficient and inexpensive perforating or punching device of the type mentioned, which will perforate or punch an object or portions of an object under movement at an angle to that of the ram or bed of a press, as the case may be, or of the ram or bed of a die-set placed within the press, and more particularly which, in a press operating in a truly vertical plane, will perforate or punch an object or part thereof under relative movement of the punch and die of a die-couple having their axes in a horizontal plane.

Another object of our invention is to provide such a device in which a perforating punch of a die-couple is disposed at an angle to an actuator operated under movement of the press, and in which rotatable means is disposed between the punch and die-couple and the actuator whereby the movement of the actuator is transferred to effect relative movement of the die-couple, preferably at a right angle to the movement of the actuator.

A still further object of our invention is to provide means of the kind described in which a housing or body portion has an actuator or prime mover vertically movable therein, a horizontally movable punch element arranged in co-operation with a horizontally-disposed die whose axis is coincident therewith, and in which housing or body portion there is a rotatable element in co-operation with said actuator and said punch member so that the punch member is actuated under movement of said actuator, and further, in which retrieving means is provided whereby all movable parts are returned to normal position.

A still further object of our invention is to provide improved mechanism whereby, under vertical or substantially vertical movement of the ram of a press, a spring-retained horizontally movable punch member is actuated in association with a horizontally disposed die-member spaced from the punch member to permit the insertion of the rim or flange of an object therebetween, so that upon forcing of the punch member into the die-member, the rim or flange is perforated or punched.

A still further object of our invention is to provide a device of the kind mentioned in which the actuator may be lengthened when it is found necessary to normally space the ram of the press or die-set a greater distance from the bed there-

of to permit the introduction between the two of a high or long object to be horizontally punched.

With the above and other objects in view to appear hereinafter, our invention consists in the combination and arrangement of parts and in the construction and co-operation of elements to be hereinafter described and more particularly pointed out in the subjoined claims.

In the drawings,

10 Fig. 1 is a vertical section through our improved perforating or punching machine or device.

Fig. 2 is a top plan view of the same.

Fig. 3 is a side view.

15 Fig. 4 is an end view, viewed from the left in Fig. 1.

Fig. 5 is a vertical section taken on line 5—5, Fig. 3.

20 Fig. 6 is a vertical section taken on line 6—6, Fig. 3.

Fig. 7 is a plan view showing the bed of a press or die-set having a plurality of perforating or punching devices positioned thereon for perforating or punching spaced-apart holes in a flange or rim of cylindrical or at least curved formation.

25 Fig. 8 is a detached perspective view of the punch member.

Fig. 9 is a detached perspective view of the 30 rotatable movement-changing or transferring element of the machine or device, whereby the movement of the actuator is transferred to movement of the punch member in a direction at an angle to that of said actuator.

35 Fig. 10 is a detached perspective view of the actuator in the form it can be used with or without an extension or lengthening element.

Fig. 11 is an end view of a modified form of 40 our invention in which the punch member is provided with a plurality of punches which project therefrom.

Fig. 12 is a section taken on line 12—12, Fig. 11.

Fig. 13 is a section similar to Fig. 12 showing 45 a still further modified form of punch member.

Referring now to the drawings in detail, the reference numeral 15 designates a portion of the bed or shoe of a die-set, or a portion of a perforating or stamping press, and 16 the punch part of our improved device which co-operates with a die part 17 positioned in spaced relation to the punch part for insertion therebetween of the sheet metal or other material to be perforated or punched. This device is preferably used in presses in which the ram or bed of the press, and in some instances both the ram and bed, are moved in a vertical or substantially vertical plane, or in connection with a die-set, the ram of which is attached to the ram of a press and the bed or shoe 50 of which is attached to the bed of the press.

This device may, however, be placed within a press in which the bed is inclined to the horizontal, as is the ram in view of the fact that in such presses the relative movement of the ram and bed is at an acute angle to the vertical; and if a die-set is inserted in a press of this kind, the ram and shoe of the die-set is correspondingly inclined and the relative movement of such parts is similar to that of the ram and bed of the press. In fact, it is our intention that this device be used on any type of press or other machine, regardless of the disposition of its parts or the direction of movement of any such parts, so long as the actuator of our device can be operated under movement of some part of the press or other machine and the movement of said actuator be transferred to the punch member, but only at an angle to that of the movement of said actuator.

As best shown in Fig. 1 of the drawings, 18 designates a sheet-metal object shown in cylindrical form and offset to form a shoulder 19 and a depending rim or flange 20 which is placed within the space between the punch part 16 of our device and the die part 17. Since this rim or flange is shown to be of considerable height, both the punch part 16 and the die part 17 are elevated, and for this purpose risers or elevating pieces 21, 22 are employed under the punch and die parts 16 and 17, respectively. Like the punch and die parts 16 and 17, these risers or elevating pieces may be of any height, as conditions require, and they are also spaced apart, as at 23, so that the rim of the sheet-metal object to be perforated or punched may extend down into this space, depending upon the level at which the rim or flange is to be punched, or upon the height of the same. These elevating pieces are secured in any approved manner to the bed of the press or to the bed or shoe of a die-set, as the case may be. The punch part 16 is bolted or otherwise fastened to the riser or elevating piece 21 when used, while the die part 17 is bolted or otherwise fastened to the riser or elevating piece 22.

The means for fastening the risers or elevating pieces to the die shoe of the die-set or to the bed of the press, and the punch and die parts 16 and 17, respectively, to the elevating pieces is not shown, since this may be accomplished in any approved manner. The die part 17 of the device comprises a die-bushing or retainer 24 which is socketed, as at 25, and receives therein a die 26 serving as the female member of a die-couple. This die is forced into the socket, and by means of a suitable tool, may be readily removed so that dies can be easily interchanged. Extending from the socket of the die-bushing is a slug-discharge passage 27 which is flared outwardly away from the die. In order to aline the inner face of the die socket with the inner face of the elevating piece 22 underneath the same, the latter is provided with a stop flange 28 against which the die-bushing bears.

The punch part of the device comprises a block-like housing or body portion 29 which is comparatively narrow and has a circular opening 30 formed transversely therethrough. In this circular opening is rotatably arranged what we term a motion transferring or changing element 31, which may be in the form of a solid cylinder, and its peripheral surface is notched at two places, designated by the numerals 32, 33, the notches being so arranged that radially-trending shoulders 34, 35 are provided which are at an angle of ninety degrees to each other, the remaining walls

36 of these notches being preferably parti-circular for a purpose to appear hereinafter.

Through the top of the housing or body portion an oil-duct 37 is formed so that the rotatable motion transferring or changing element 31 may be properly lubricated for free action. The housing is bored out from the top, as at 38, so that a portion of the bore thus formed intersects the marginal portion of the circular opening 30. A second bore 39 is formed in the housing near its lower end which is disposed at a right angle to the bore 38. The bores 38 and 39 therefore intersect each other, and normally the bore 38 is vertically disposed while the bore 39 is disposed horizontally. In the bore 38 a cylindrical actuator or prime mover 40 is arranged, it having a reduced upper end to form an upwardly-facing shoulder 41. Fastened to the top of the housing by means of screws or otherwise is a retainer plate 42 having an opening therein through which the reduced upper end of the actuator extends, and in which said upper end is freely slideable. This retainer plate overhangs the bore 38, and this serves as a stop for the shoulder 41 of the actuator. The actuator 40 is cut away from its lower end upwardly at one side thereof to form a downwardly-facing shoulder 43 which is in engagement with the radially-trending shoulder 34 of the motion-transferring or changing element 31.

In the horizontal bore 39 a spring-retained plunger 44 is longitudinally movable, and it has a plunger rod 45 threaded into one end thereof which is slideable in an abutment plate 46 closing one end of the horizontal bore 39. Surrounding the plunger rod 45 is a spiral spring 47 serving as a compression spring and bearing at one end against the abutment plate 46 and at its other end against a collar 48 adjustable along the plunger rod and retained in adjusted position by an adjusting nut 49 threaded onto said rod and bearing against the collar 48 so as to retain the spring 47 under desired compression. A lock nut 50 is applied to said rod and bears against the adjusting nut 49 so as to prevent unthreading of the latter. The opposite end of the plunger is axially socketed, as at 51, and fitted therewith is a punch 52 which may have any desired shape and its outer end may be of any desired diameter, depending upon the punch opening in the die 26 which is to receive the same. This punch is provided with a notch 53 near its inner end to receive the reduced and unthreaded inner end of a securing screw 54 threaded into a diagonally-disposed tapped opening formed in the plunger. In this manner the punch is securely but removably fastened into the plunger, thus allowing ready replacement of punches of different sizes. It is of course apparent that the axes of the die 26 and the punch 52 are coincident.

This punch is associated with a stripper piece or head 55 which rests upon the riser or elevating piece 21 and is secured to that end of the housing adjacent the die 26 so as to surround the punch. This stripper piece or head is provided with a bore or passage 56 which is reduced in diameter step by step from its inner end outwardly. The largest or innermost portion of this bore or passage is of a diameter conforming to that of the plunger bore 39, and this may, depending on the thickness of the stock being punched or perforated and the movement of the ram of the press, receive the adjacent end of the plunger. The intermediate portion of this bore or passage is of a size to permit the free en-

trance thereinto of the largest portion of the punch projecting from the plunger, and the smallest or outermost portion of this bore or passage is of a size to allow the extremity or punch portion of the punch to be guided thereby or pass freely therethrough, as may be desired.

In the embodiment of our invention illustrated, both the actuator 40 and the plunger 44 are cylindrical, but these may be otherwise formed in cross section if desired. When the plunger is used in cylindrical form, it has a key 57 secured thereto which is slideable in a key way 58 formed in the plunger bore 39, thus preventing rotation of said plunger. The plunger is provided with a notch 59 so as to form a shoulder 60 thereon which is engaged by the radial shoulder 35 formed on the motion-transferring or changing element 31. When employing a cylindrical actuator and a cylindrical plunger, the notches 32 and 33 in the motion-transferring or changing element 31 and the notch 59 in the plunger are provided with the curved walls 36 so that portions of the actuator and plunger may fit within said notches. When, however, the actuator and plunger are given a square or other cross-sectional formation, a change in the form of the notches 32 and 33 is made so as to conform to the cross-sectional shape of the actuator and plunger. In the event that the plunger is given a cross-sectional shape which will not permit its rotation within its receiving bore, the key 57 may be dispensed with, as this key is used only to guard against rotation of a cylindrical plunger, which would cause the notch therein to become disaligned with its co-acting notch in the motion-transferring or changing element 31.

In Fig. 1 we have shown only a portion of a cylindrical object to be perforated or punched, but the broken upper end of this object indicates considerable height for the same, necessitating adjustment of the ram of a press and the ram of a die-set when used in a press, so that it will be normally spaced a considerable distance above our device; it being necessary to provide sufficient clearance between the ram and bed for insertion of the object to be perforated or punched therebetween. In such instances provision is made so that the ram in its movement, or the bed, as the case may be, will not strike an inserted object to be perforated or punched. For this reason the upper end of the actuator 40 is axially bored and tapped, as at 62, and an extension or lengthener 63 shown in dotted lines in Fig. 1, and partly shown in Fig. 3, is attached to the actuator proper, the extension having at its lower end an axial stud (not shown) which is adapted to be threaded into the tapped bore 62, and the striking end of the actuator, thus lengthened, reaches a level which is above the highest point of the object inserted in the press or die-set, so that the movement of the ram, or the bed of the press, as the case may be, need not be increased and merely an adjustment for proper spacing between the ram and bed is required. These actuator extensions may be of different lengths, or several extensions may be connected together, in which case each extension has a threaded stud at its lower end and a tapped bore at its upper end, or vice versa. Therefore, where in the claims reference is made to an actuator without specifying the actuator extension or extensions, it is intended to mean an actuator with or without the extension.

As shown in Fig. 1, the actuator has been depressed sufficiently by the ram of the die-set or

press to cause rotation of the motion-transferring or changing element 31, which in turn has caused movement of the plunger 44 toward the left against the force of the spring 41, such movement having projected the punch 52 through the stripper head 55, and the rim or flange 20 of the object or article inserted in the press, with the result that the punch has entered the die and caused the slug to be punched from the object and passed into the die, from which it passes into the passage 27. The slugs are delivered through the passage 27 and fall onto the shoe of the die-set or bed of the press, as the case may be, from which they can be removed at convenient times.

In Fig. 7 we have illustrated a plurality of punching or perforating devices mounted on the shoe of a die-set or the bed of a press, prepared to punch or perforate a circular or arcuate rim or flange at spaced-apart points. The distances between such points may of course be increased or diminished, as required. In this particular arrangement, the punching or perforating devices are radially disposed, and upon lowering the ram of a press or raising the bed of a press, as the case may be, the rim or flange shown is punched out or perforated at three points.

In Figs. 11 to 13 we have shown plungers provided with a plurality of punch points. In Figs. 11 and 12 the plunger illustrated is of square formation in cross section, but may be given any other cross-sectional form. It has secured to one end thereof a punch plate 64 by means of screws 65. At any desired points in this punch plate, punch-receiving holes 66 are drilled, and the inner ends thereof enlarged, as at 67. In each of these punch-receiving holes a punch 68 is inserted from the inner side of the plate, and each punch has an enlargement or head 69 at its inner end which is entered in the enlarged portion 67 of the punch hole. These punches are shown of cylindrical formation, but may have any other desired shape in cross section, and the heads 69 of the punches may also be cylindrical or they may be formed non-cylindrical, depending on the security desired to prevent rotation of the punches within their heads. These punches may be cylindrical throughout and may have a driven fit within the punch head, but in all cases the heads of these punches bear against the outer end of the body portion of the plunger, as clearly shown in Fig. 12, so that the thrust, when forcing the punches through sheet metal or the like, will be received directly by said body portion.

In Fig. 13 the plunger is shown of cylindrical form, or at least that end thereof to which the punches are to be secured is so formed, to permit of applying thereto a plunger cap 70 socketed and internally threaded to receive the outer ends 60 of the plunger. Through this cap the punches 68 are passed, they being retained in place in the same manner as described with reference to the punches illustrated in Figs. 11 and 12. It is of course understood that when using a plunger of the type shown in Figs. 11 to 13, the stripper piece or head 55 is correspondingly formed to permit all the punches to pass therethrough and through any material interposed between the punch and die parts of the device.

The motion-transferring or changing element 31 is retained in the block-like housing or body portion 29 by reason of the actuator 40 and the plunger 44 having portions thereof entered into the notches 32 and 33 of said motion-transferring or changing element. However, if de-

sired, end plates 71 may be applied to opposite sides of the housing, and these are secured to the housing by means of screws 72. Ordinarily we prefer to dispense with these end plates.

Having described our invention, what we claim is:

1. A rim or flange perforating or punching device adapted to be placed within a press or a die-set having a ram and bed movable relatively in a given plane, a punch and die-couple positioned between said ram and bed and whose members are relatively movable at an angle to said given plane, a rectilinearly movable actuator adapted to be moved by a part of the press or die-set, and a cylindrical rotatable converter having peripheral engaging-means engaged and operated by said actuator and transferring movement from said actuator to one of the parts of said punch and die-couple.

2. In a device for punching holes in a rim or flange of a part having said rim or flange positioned vertically in a press or a die-set placed within a press, a punch and die-couple whose axis is horizontally disposed and which is supported on the bed of the press or die-set and has the rim to be punched between the punch and die of said punch and die-couple, a vertically movable actuator adapted to be engaged by the ram of the press or die-set, a cylindrical rotatable element peripheral engaging-means engaged and rotated by said actuator and additional peripheral engaging-means circumferentially spaced from said first-mentioned engaging-means, and a horizontally movable element engaged by the additional engaging-means of said cylindrical rotatable element to cause movement of said horizontally movable element, the latter having the punch of said die-couple removably attached thereto so as to force the same through said rim or flange upon actuation of said actuator.

3. A perforating device adapted to be placed within a press or a die-set having a ram and bed movable relatively in a given plane, comprising a punch and die-couple supported on said bed and whose axis is disposed at an angle to said plane and between the members of which the article to be punched is placed, an actuating rod adapted to be actuated under relative movement of said bed and ram, a rotatable element having spaced-apart shoulders, one of which is engaged by said actuating rod, a plunger movable at an angle to said actuating rod and engaged by the other shoulder of said rotatable element, and means to normally retain said actuator rod, rotatable element and plunger in normal position, one member of said die-couple being carried by said plunger.

4. A perforating device adapted to be placed within a press or a die-set having a ram and bed movable relatively in a given plane, comprising a housing supported by said bed, a cylindrical rotatable element within said housing, an actuator rod longitudinally slidable in said housing peripherally engaging said rotatable element to actuate the same and adapted to be actuated under movement of said ram, a plunger longitudinally movable at an angle to said actuator rod and peripherally engaged by said cylindrical rotatable element so as to be actuated under rotation thereof, a punch projecting from said plunger,

er, a stripper through which said punch is adapted to be passed, and a die retainer also supported on said bed and having a die therein adapted for co-action with said punch.

5. In a perforating device adapted to be placed within a press or a die-set having a ram movable toward and from said bed, a housing supported by said bed, an actuator rod vertically movable in said housing and adapted to be actuated by said ram, a rotatable element peripherally notched to form spaced-apart shoulders, one of which is engaged by said actuator rod, a plunger horizontally movable in said housing and engaged by the other shoulder of said rotatable element, means to retain said actuator rod, rotatable element and plunger in normal position, a stripper at one end of said housing, a punch axially and removably applied to said plunger and designed to be projected through said stripper, a die retainer also supported by said bed and separated from said stripper and said punch by an intervening space, and a die applied to said die retainer and having its axis coincident with that of said punch.

25 6. In a perforating device adapted to be placed within a press or a die-set having a bed and a ram movable toward and from said bed, a housing supported by said bed, an actuator rod vertically movable in said housing and adapted to be actuated by said ram, a rotatable element peripherally notched to form spaced-apart shoulders, one of which is engaged by said actuator rod, a plunger horizontally movable in said housing and engaged by the other shoulder of said rotatable element, a plunger rod extending from one end of said plunger out of said housing, a collar adjustable on said plunger rod, a spring surrounding said plunger rod and bearing at one end against said housing and at its other end against said collar, a punch projecting from the opposite end of said plunger, and a die co-operating with said punch and supported by said bed.

7. In a perforating device adapted to be placed within a press or a die-set having a bed and a ram movable toward and from said bed, a housing supported by said bed, a cylindrical actuator rod vertically movable in said housing and adapted to be actuated by said ram, a rotatable element peripherally notched to form substantially radially-disposed shoulder walls and having the remaining walls of the notches parti-circular, said actuator rod having its lower end cut away to form a downwardly-facing shoulder engaging the shoulder wall of one of said notches and having the region of said rod directly above said shoulder entered into said last-mentioned notch, a cylindrical plunger horizontally movable in said housing and having a notch therein forming a shoulder engaging the shoulder wall of the other notch of said rotatable element, that portion of the plunger adjacent the shoulder thereof being entered in the last-mentioned notch of said rotatable element and the punch of said punch and die-couple being carried by said plunger, and resilient means to cause said plunger to be retained in normal position and to thereby return said rotatable element and actuator rod to normal position when said actuator rod is relieved of pressure from said ram.
